UNITED STATES PATENT OFFICE.

OWEN LANNON, OF LEE, MASSACHUSETTS.

DESIGN FOR A PIPE-WRENCH JAW.

SPECIFICATION forming part of Design No. 31,142, dated July 4, 1899.

Application filed June 1, 1899. Serial No. 719,044. Term of patent 14 years.

To all whom it may concern:

Be it known that I, OWEN LANNON, a citizen of the United States, residing at Lee, in the county of Berkshire and State of Massachusetts, have invented and produced a certain new and original Design for Pipe-Wrench Jaws; and I do declare the following to be a full, clear, and exact description of the invention, such as will enable others skilled in the art to which it appertains to make and use the same.

The invention relates to a new and original design for a pipe-wrench jaw; and it consists of the design shown in the accompanying drawing, in which I have represented my invention in perspective.

The leading feature of the design comprises the bar 1, one end of which is rounded, as shown at 2, and having a straight smooth lower edge 3, and a head 4 of greater width

throughout its entire length than the bar 1 and formed with flat sides 4' and with a curved rear end 5 and a toothed face 6. The upper surface of this bar is smooth for a portion of its length, as shown at 7, and then has 25 its remaining portion formed with transverse teeth 8.

9 denotes a horizontal line of transverse apertures.

What I claim is—

The design for a pipe-wrench jaw, as herein shown and described.

In testimony whereof I have hereunto set my hand in presence of two subscribing witnesses.

OWEN LANNON.
